UNITED STATES PATENT OFFICE.

INEZ SCOTT JEROME, OF CHICAGO, ILLINOIS.

BRASSIÈRE.

Application filed April 21, 1921. Serial No. 463,247.

To all whom it may concern:

Be it known that I, INEZ SCOTT JEROME, a citizen of the United States, residing at Chicago, in the county of Cook and State of Illinois, have invented certain new and useful Improvements in Brassières, of which the following is a specification.

My invention relates to improvements in brassières, and is well adapted for use in 10 a brassière which may be worn under or over the corset.

The principal objects of the invention are to provide a brassière which may readily be adapted to different styles of figure; to provide 15 an article of such construction that a given size or model can be used by women having figures differing considerably in size so that it is not necessary to carry in stock more than a very few sizes and styles; to 20 provide a brassière which will fit the person of the wearer perfectly, applying pressure at the requisite points without undue discomfort; to provide a brassière which may be manufactured with rapidity and economy 25 and which will be ornamental, durable and efficient, and in general to provide an improved brassière of the character referred to.

In the drawings, which illustrate a preferred application of my invention,

30 Fig. 1 is a front view in perspective of my improved brassière as worn under the corset;

Fig. 2 is a rear perspective view of the brassière, and

35 Fig. 3 is a front view of the brassière opened out flat.

Referring to the drawings, it will be seen that the main portion of the brassière comprises a front portion 10 of suitable woven 40 goods of any desired grade. At points substantially under the arm pits, the sides of the front portion 10 are connected to rearwardly extending side extensions 11 and 12. The center line of the front piece 10 is made 45 with a dart 12^a extending upwardly from the lower edge of the front, so that the lower edge will fit properly. The parts 11 and 12 are made with darts 13 and 14 extending from the lower edge 15 of the garment approximately $\frac{3}{8}$ ths of its height so as to bring the ends of the flaps 16 and 17 of the side extensions 11 and 12 into the proper position when the brassière is put on.

At the junctions between the rear sections 50 11 and 12 and the sides of the front piece 10, bones 18 and 19 are employed to hold the

parts properly in position. Boning is also applied to the rear sections 11 and 12 at the points marked 20, 21, 22 and 23, so that the back part of the garment will properly maintain its shape. The upper margins of the back parts 11 and 12 are made angular or curved as shown at 24 and 25 to connect with the shoulder straps 26 and 27 which comprise simple loops, the front ends of 60 which are connected to the upper edge or margin 28 of the front piece over the busts.

It has been stated that the front piece of the garment is shaped to fit the person of the wearer. At the sides over the busts, this result is effected by making the sides of the front wide enough, (from top to bottom of the garment) to provide excess material so that when the edges 15 and 28 of the front piece are sewed to the adjacent edges of the rear sections 11 and 12, there will be formed 70 pocket-like puckers 29 and 30. That is to say, before the front piece 10 is sewed to the rear sections 11 and 12, the corners of the front piece are drawn toward each other, thus forming puckers in the side edges of the front piece, so as to bring the corners of the front section in register with the adjacent corners of the rear sections. The rear 75 edges of said puckers 29 and 30 are gathered together and sewed to a pair of loops or rings 31 and 32 located somewhat below the median line of the garment so that when draft is exerted on said rings 31 and 32, the 80 pockets 29 and 30 will be drawn toward the 85 back and also downwardly.

In putting on the brassière, the arms are inserted through the shoulder straps in the ordinary manner and by means of the tape or string 33, the rear section is drawn around to the back. The end of the tape 33 is then inserted through a horizontally extending slit 34 in the other back section 12 so that it may pass through the ring 32. The flap 17 is then brought over the end of flap 16 to the back section 11 and the end of the string 35 is passed through the opposite ring 31. The ends of the strings 33 and 35 are then drawn together to secure the desired fit or pressure and are tied together as shown at 36.

It will be observed that the strings 33 are located somewhat lower than the median line of the garment. Hence, in order to hold down snugly the upper portions of the flap members 16 and 17, I prefer to make use of an auxiliary string 37 which passes

through an eyelet 38 in the flap 12 and the ring 39 sewed to the outside of the other flap 16.

5 The brassière may be worn over or under the corset, although in most cases it will be found desirable to wear the same under the corset. Also, the front may be held down, if desired, by a strap 40 equipped with an adjustable hook 41, which can be engaged 10 with the front of the corset after putting on the latter.

It will be observed that because of the doubling back of the ends of the strings 33 and 35 through the rings 31 and 32, I am 15 enabled to secure a very considerable drawing down effect on the parts 29 and 30 thus aiding to secure the desired flat front effect. At the same time, the pressure is so applied that the wearer suffers the least possible 20 discomfort.

The scope of the invention should be determined by reference to the appended claims, said claims being construed as broadly as possible, consistent with the state 25 of the art.

I claim as my invention:

1. A brassière comprising a front piece having rearwardly extending side extensions, loops on the sides of said front piece substantially under the arm pits, and fastening means on each of said side extensions adapted to pass around the back of the wearer and engage the loop on the opposite side of the front piece.

35 2. A brassière comprising a front piece overlying the busts and provided with rearwardly extending side extensions, loops on the side portions of said front piece beneath the arm pits, and draw strings on said extensions adapted to extend behind the back 40 of the wearer and freely pass through the

loops on the opposite side of the front piece, the said strings being then drawn rearwardly and tied together.

3. A brassière comprising a front piece 45 overlying the busts and provided with rearwardly extending side extensions, means for drawing the rear portions of said extensions together, loops attached to the side portions of said front piece substantially beneath the 50 arm pits, and a draw string attached to the rear portion of each of said extensions below the median line and adapted to be inserted through the loop on the opposite side portion of the front piece, the ends of said 55 strings being then drawn rearwardly and tied together behind the back of the wearer.

4. A brassière comprising in combination a front piece of woven fabric having rearwardly extending extensions, the ends of 60 which overlap on the back of the wearer, strings connected to the ends of said overlapping portions and means connecting said strings to the sides of the front piece located substantially under the arm pits of 65 the wearer, said connections comprising loops through which the strings pass freely, the ends of the strings being secured together intermediate said loops.

5. A brassière comprising in combination 70 a front piece of woven fabric having integral rearwardly extending extensions, strings connected to the ends of said extensions, and means connecting said strings to the sides of the front piece located substantially under the arm pits of the wearer, said connections comprising loops through which 75 the strings pass freely, the ends of the strings extending rearwardly and being secured together intermediate said loops.

INEZ SCOTT JEROME.
